UNITED STATES PATENT OFFICE.

HUGH M. MASTERTON, OF PATERSON, NEW JERSEY.

GUN ATTACHMENT.

1,239,287.

Specification of Letters Patent. Patented Sept. 4, 1917.

Application filed June 23, 1915. Serial No. 35,901.

To all whom it may concern:

Be it known that I, HUGH M. MASTERTON, a citizen of the United States, residing at Paterson, in the county of Passaic and State 5 of New Jersey, have invented a new and useful Gun Attachment, of which the following is a specification.

The device forming the subject matter of this application is an auxiliary barrel for 10 a fire arm.

One object of the present invention is to provide a means whereby a barrel having a bore of relatively large diameter, and of center fire construction, may be adapted for 15 use in connection with a barrel of smaller bore and using a rim fire cartridge.

It is within the province of the disclosure to improve generally and to enhance the utility of devices of that type to which the 20 present invention appertains.

With the above and other objects in view which will appear as the description proceeds, the invention resides in the combination and arrangement of parts and in the 25 details of construction hereinafter described and claimed, it being understood that changes in the precise embodiment of the invention herein disclosed can be made within the scope of what is claimed, without departing from the spirit of the invention.

In the accompanying drawing:

Figure 1 is a longitudinal sectional view of a shot gun barrel wherein the present invention has been mounted, parts being 35 broken away;

Fig. 2 is an end elevation of the structure shown in Fig. 1;

Fig. 3 is a cross section on the line 3—3 of Fig. 1;

Fig. 4 is an elevation showing the muzzle of the structure embodied in Fig. 1;

Fig. 5 is a composite perspective view showing one of the carrying members and its extractor, the carrying member being in 40 section.

In the drawings there is shown a shot gun barrel 1 provided with a bolt lug 2, the barrel 1 having bores 3 equipped with seats 4 adapted to receive the rim of a shell, the 45 extractor being shown at 5 and having grooves 6 constituting parts of the seats

4. No novelty is claimed for the foregoing structure saving in so far as it may enter into combination with elements hereinafter 50 described, and it will be understood readily by those skilled in the art, as the descrip-

tion of the present invention progresses, that the device forming the subject matter of this application is adapted to be employed in connection with either a single barrel shot gun or a double barrel shot gun. Although a matter of common knowledge, it may be stated incidentally that shot gun cartridges at present are of center fire construction.

In carrying out the present invention 65 there is provided an auxiliary barrel 7 which may be bored for shot or calibered for ball, the bore of the barrel 7 being equipped with a seat 9 adapted to receive the rim of a rim fire cartridge 10. The invention contemplates the use of a carrying member 8 in the form of a tube, having an eccentric opening 11 in which the breech of the auxiliary barrel 7 is received. The carrying member 8 is provided, as shown in Fig. 5 with 70 a threaded opening 21 receiving a set screw 20 whereby the carrying member may be connected to the auxiliary barrel 7 adjustably. The carrying member 8 embodies a parti-circumferential flange 12 adapted to be received in the seat 4 of the main barrel 1. In the carrying member 8 there is formed a slot 14 adapted to receive the shank 15 of an auxiliary extractor 16 comprising a head 17 having a groove 18 constituting a 75 continuation of the seat 9 of the auxiliary barrel 7. The head 17 embodies a depending flange 19 adapted to be received in the seat-forming groove 6 of the extractor 5, so that when the extractor 5 is actuated, the 80 extractor 16 will be actuated also.

The invention comprises a carrying member 22 having an eccentric opening 23 receiving the muzzle of the auxiliary barrel 7, a set screw 24 being threaded into the member 22, and being adapted to engage the 85 muzzle of the auxiliary barrel 7.

In practical operation, the auxiliary barrel 7, together with the carrying members 8 and 22 are located inside of one of the 100 bores of the main barrel 1. Owing to the eccentric position of the openings 11 and 23 in the respective carrying members 8 and 22, the auxiliary barrel 7 will be lowered sufficiently so that the firing pin (not shown) of 105 the barrel 1 will coat with the rim of the cartridge 10.

From the foregoing it will be observed that a large bore arm of center fire construction may be converted readily into a 110 small bore arm of rim fire construction. Such an operation lessens the cost of shoot-

ing, since a large bore shot gun may be transformed into a small bore shot gun, or, at the will of an operator, may be converted into a small bore rifle, a change at the same time being made from center fire ammunition to rim fire ammunition.

The carrying members 8 and 22 may be shifted circumferentially on the auxiliary barrel 7 and may be held in place by the set screws 20 and 24. Since the openings 11 and 23 in the carrying members are eccentrically disposed, it is possible to position the auxiliary barrel 7 properly with respect to the main barrel 1, so that the sights of the main barrel will be effective when the auxiliary barrel is used.

Briefly considered, the device forming the subject matter of this application includes a main barrel 1 and a main extractor 5 operating in the breech in the main barrel 1, the extractor and the breech of the main barrel being provided with a circumscribing seat 4. A tubular carrying member 8 is mounted in the main barrel and has a parti-circumferential flange 12 received in the seat 4. The ends of the flange 12 are spaced, as shown at 50, from the ends 51 of the main extractor 5, to permit the carrying member 8 to be rotated on its axis 30 through a small arc, thus adjusting the posi-

tion of the auxiliary barrel 7 which is eccentrically mounted in the carrying member.

Having thus described the invention, what is claimed is:—

In a device of the class described, a main barrel; a main extractor operating in the breech of the main barrel, the extractor and the breech of the main barrel being provided with a circumscribing seat; a tubular carrying member mounted in the main barrel and having a parti-circumferential flange received in the seat, the ends of the flange being spaced from the ends of the main extractor to permit the carrying member to be rotated on its axis, the carrying member having an eccentrically disposed opening; an auxiliary barrel mounted in the opening of the carrying member; means for holding the auxiliary barrel against rotation in the carrying member; and an auxiliary extractor cooperating with the auxiliary barrel, and operated by the main extractor.

In testimony that I claim the foregoing as my own, I have hereto affixed my signature in the presence of two witnesses.

HUGH M. MASTERTON.
